UNITED STATES PATENT OFFICE.

PHILIP CHARLES LAWLESS, OF LONDON, ENGLAND.

AUTOMATIC WIPER FOR USE IN LINOTYPE-MACHINES.

SPECIFICATION forming part of Letters Patent No. 687,691, dated November 26, 1901.

Application filed May 16, 1901. Serial No. 60,546. (No model.)

To all whom it may concern:

Be it known that I, PHILIP CHARLES LAWLESS, of 188 Fleet street, in the city of London, England, have invented certain new and useful Improvements in Automatic Wipers for Use in Linotype-Machines; and I do hereby declare the following to be a full, clear, and exact description of the invention, such as will enable others skilled in the art to which it appertains to make and use the same.

The present invention relates to improvements in automatic wipers for use in linotype-machines, and has more particular reference to an automatic wiper for the mouth-piece of the metal-pot of the Mergenthaler linotype-machine, described in the specification of Letters Patent No. 436,532, of September 16, 1890. In that machine the mold in which the linotype is cast is a slot in and through a block which is made fast to a so-called "mold-wheel," the length of the slot being parallel with a diameter of the wheel and its width parallel with the wheel's axis. One side of the mold-block presents itself to the rear of the mold-wheel, and it is up to that side that the metal-pot advances, making a metal-tight fit therewith and maintaining it, if not prevented, during the injection of metal into the mold, the metal-pot being withdrawn into its normal position after the linotype has been cast; but the metal-tight fit above mentioned is constantly being prevented. Thus the row of metal-ports in the mouthpiece frequently extend beyond the mold-slot, and then the ports beyond the latter register with blank surface of the mold-block, when disks or splashes of metal will form over and around the mouths of these ports, or as the metal-pot moves back metal may trickle down the mouthpiece and set there. Such splashes and trickles, especially the latter, prevent the mouthpiece fitting metal-tight up to the mold-block the next time it moves up to the latter, so that when metal is then injected some of it will splash.

An automatic wiper similar to those for wiping the trimming-knives of the machine would probably have been applied to the mouthpiece above mentioned had it not been that whereas the knife-wipers act with a reciprocating linear motion derived from a source outside their plane of action the mold-

wheel has a rim or flange projecting from its edge in the direction of the mouthpiece for a distance very nearly equal to the travel of the latter, thereby practically inclosing the space between the mold-wheel and mouthpiece and shutting it off from outside agencies, and a wiper fast to the rear face of the mold-wheel and projecting therefrom far enough to wipe the mouthpiece each time it passes it is impracticable, because it would be cut off by the fixed knife that trims the foot of the newly-cut linotype.

The present invention consists in a wiper for the mouthpiece of the metal-pot adapted to work within the circle of the mold-wheel and actuated in one direction by the motion through a certain arc of a stud on the said wheel and in the other by the resilience of a spring and which resilience is generated by the said motion.

The essence of the invention resides in the provision of a mechanically-actuated wiper lying between the mold-disk and the mouth of the pot and adapted to act on the latter, this wiper having a motion independent of the mold-disk, so that it will not conflict in operation with other parts.

Referring to the accompanying drawings, which are to be taken as part of this specification and read therewith, Figure 1 is a rear elevation showing the mold-wheel holding its stud in contact with the wiper-arm and just about to start upon its first arcual motion; Fig. 2, a vertical section in the plane of the mold-wheel axis, including parts of the first elevator, vise-frame, metal-pot, and mold-wheel slide and showing the wiper half-way along the metal-pot mouthpiece; Fig. 3, a front elevation showing the wiper nearly at the end of its wiping motion along the metal-pot mouthpiece, the dot-and-dash lines indicating the relative position of the mold-wheel; Fig. 4, a rear elevation, and Fig. 5 a detail plan, together illustrating two modifications.

C is the newly-cast linotype; N', part of the head of the first elevator or yoke that carries the composed line of matrices and space-bars; O, the mold-wheel; o', its axle; o², the bearing of the latter; o³, an arm springing from the mold-wheel slide o⁴ to carry the bearing o⁵; o¹³, the mold-block; P, the abutment

between which and the mold-block o^3 the composed line above mentioned is clamped; V , part of the metal-pot, and v the mouthpiece of it.

- 5 The motions of the mold-wheel O and metal-pot V of the Mergenthaler linotype-machine are as follows: The mold-wheel O , holding its mold-block o^3 at the top, moves toward the abutment P to clamp the composed line, 10 and the metal-pot V moves forward till its mouthpiece v fits metal-tight against the rear face of the mold-block, whereupon metal is injected through the mouthpiece v into the slot, thereby casting the linotype C . The 15 mold-wheel O then moves in the direction indicated by the arrows in Figs. 1, 3, and 4 through an arc of two hundred and seventy degrees and stops for the linotype C to be ejected from the slot. It then moves through 20 a quarter of a circle up into the first-mentioned position.

The above-mentioned parts and motions of the metal-pot and the mold-wheel are as heretofore.

- 25 1 is a spiral spring standing around the bearing o^2 and having one end made fast to the arm o^3 at 2, which serves it as a base independent of the rotary motion of the wheel O .

30 3 is the wiper-arm. It is for the purpose of this invention a continuation of the other end of the spring 1 and radial to the axis of the mold-wheel O .

- 35 4 is the wiper, fixed upon the arm 3 by any suitable means. It is of leather or other material or materials suitable for the purpose. So long as the wiper 4 is out of action the resilience of the spring 1 keeps it up to a buffer or cushion 5, fast on the slide o^4 , as shown in Figs. 1 and 4.

- 40 45 6 is a stud fast to and projecting to the rear from the mold-wheel O far enough to engage the arm 3. This stud is so positioned upon the mold-wheel O and the arm 3 so shaped that it is in practical engagement with the latter at the moment when the mold-wheel O starts upon its three-quarters-of-a-circle motion, as shown in Figs. 1 and 4.

- The action of the invention in wiping the mouthpiece v is as follows: The stud 6 pushes 50 the wiper-arm 3 before it, thereby making the wiper 4 wipe the face of the mouthpiece v . This action of the stud and wiper is illustrated in Fig. 3. As soon as the wiper 3 has passed the mouthpiece v , which happens 55 when the stud 6 reaches the position indicated by dotted lines in Fig. 3, it becomes necessary to disengage the arm 3 from the stud 6 for the purpose of leaving the wiper free to be returned to its original position 60 by the resilience of the spring 1 and to thereby wipe the mouthpiece a second time. The first or single wiping may suffice for a small mouthpiece; but the double wiping is preferred, as being more reliable than a single one. Two disengaging devices are illustrated, one in Figs. 1, 2, and 3 and the other in Figs. 4 and 5. The former device consists

of a horn 7, fixed to the arm o^3 and holding a cam-surface 8 in the path of the wiper-arm 3, the zero of this surface being to the front 70 of the said path and the maximum to the rear of it, so that as soon as the wiper 4 has passed the mouthpiece v the surface 8 pushes the wiper-arm 3 to the rear clear of the stud 6, the rise of the said surface and the length of 75 the stud 6 being proportioned to produce that result at the time stated, whereupon the resilience of the spring 1 returns the wiper 4 to its original position. The device illustrated in Figs. 4 and 5 consists in a combination of eccentricity of the spring 1 with an adjustable contact-piece on the wiper-arm 3 for the stud 6 to engage with. Its spring (marked 1^a to distinguish it from the spring 1 in Figs. 1 to 3) is eccentric to the bearing o^2 , with its center below the axis of that bearing. This center may equally be above the said axis.

9 is the contact-piece above mentioned. It is adjustable lengthwise of the wiper-arm 3 90 by means of a set-screw 10. The respective paths of the stud 6 and the contact-piece 9 being eccentric to each in the way stated, the stud 6 moves up the side of the contact-piece 9 during the wiping action of the wiper 4 and off it at the moment the wiper 4 has passed the mouthpiece v , whereupon the resilience of the spring 1^a returns the wiper 4 to its original position. The radial length of the side of the contact-piece 9 is adjusted to keep 95 the stud 6 in contact with it for the proper time. The reason why the contact-piece 9 is adjustable lengthwise of the arm 3 is the necessity of compensating for wear between it and the stud 6. Otherwise the contact-piece 105 might be an enlargement of the arm 3 and fast to it.

The cam-surface 8, above described, may also be relied on to disengage the wiper-arm 3 when the spring is eccentric to the bearing o^2 instead of the contact-piece 9, in which case its action will be as described above with reference to Figs. 1 to 3.

If the spring is concentric with the bearing o^2 , it may fit practically close to it, in which 115 case the bearing o^2 will serve as a support for it. Hence a concentric spring may be of thinner material than an eccentric one, as shown in the figures, because it has not to bear the weight of the arm 3, but has only to return 120 the latter and the wiper 4. When the two are concentric, it is preferred that a thin ring 11 should be interposed to prevent friction between the coils of the spring and the bearing o^2 to prevent the torsional strain on the 125 arm 3 due to the contact of the wiper 4 and the mouthpiece v twisting the said arm and to steady the motion of the latter.

It is a matter of indifference whether the spring and wiper-arm are in one continuous 130 piece or in two separate pieces joined together. They must be practically fast to each other in order that the first wiping motion of the arm may wind up the spring and the resili-

ence of the latter return the arm. Fig. 4 shows the former, and Figs. 1 to 3 the latter, construction. The junction between them may be effected by any suitable means. Referring to Figs. 1 to 3, advantage is taken of the presence of the ring 11 to fasten the respective ends of the wiper-arm 3 and the spring to it, 12 being an enlargement of the said end of the arm 3; 13, a tab or prolongation of the enlargement 12, the enlargement 12 having a hole to receive the outwardly turned end 14 of the spring and both a groove which fits over the spring, and 15 15 screws passed through the tab 13 into the ring 11.

15 I claim—

1. In a linotype-machine and in combination with its metal-pot and mold-wheel, a wiper for the mouth of the metal-pot, working within the circle of the mold-wheel, a stud 20 on said wheel to move the wiper in one direction, and a spring to move it in the reverse direction.

2. The combination with the metal-pot and the mold-wheel of a linotype-machine, of a wiper for the mouthpiece of the metal-pot; an arm radial to the axis of the mold-wheel and carrying the said wiper on its outer end; a spiral spring surrounding the bearing of the mold-wheel, fast by one end to a base 25 independent of the rotary motion of the mold-wheel and having the said arm practically fast to its other end; a stud on the mold-wheel engaging the said arm to make the wiper wipe the mouthpiece; and means for 30 disengaging the said arm from the stud after the mouthpiece has been wiped and leaving it free to be returned to its original position by the resilience of the spring.

3. The combination with the metal-pot and 40 mold-wheel of a linotype-machine, of a wiper for the mouthpiece of the metal-pot; an arm radial to the axis of the mold-wheel and carrying the said wiper on its outer end; a spiral spring surrounding the bearing of the mold- 45 wheel, fast by one end to a base independent of the rotary motion of the mold-wheel and having the arm practically fast to its other end; a stud on the mold-wheel engaging the arm to make the wiper wipe the mouthpiece; and a cam-surface for disengaging the arm 50 from the stud as soon as it has been wiped and leaving it free to be returned to its original position by the resilience of the spring as soon as such wiping has been effected.

55 4. The combination with the metal-pot and the mold-wheel of a linotype-machine, of a wiper for the mouthpiece of the metal-pot; an arm radial to the axis of the mold-wheel and carrying the said wiper on its outer end;

a spiral spring surrounding the bearing of 60 the mold-wheel eccentrically to the axis of it, fast by one end to a base independent of the rotary motion of the mold-wheel and having the said arm practically fast to its other end; a contact-piece adjustable lengthwise of the 65 arm; a stud on the mold-wheel to engage the said contact-piece to make the wiper wipe the mouthpiece and to leave it free to be returned to its original position by the resilience of the spring, as soon as such wiping has 70 been effected.

5. The combination with the metal-pot and the mold-wheel of a linotype-machine, of a wiper for the mouthpiece of the metal-pot; an arm radial to the axis of the mold-wheel and carrying the said wiper on its outer end; a spiral spring surrounding the bearing of the mold-wheel eccentrically to the axis of it, fast by one end to a base independent of the rotary motion of the mold-wheel and having the 75 said arm practically fast to its other end; a contact-piece on the arm; a stud on the mold-wheel to engage the said contact-piece to make the wiper wipe the mouthpiece and to leave it free to be returned to its original position by the resilience of the spring, as soon as such wiping has 80 been effected.

6. In a linotype-machine the combination of the pot-mouth, the wiper, the spring tending to move the wiper in one direction, and 85 means actuated by the mold-disk for moving the wiper a limited distance in the opposite direction.

7. In a linotype-machine, the mold-disk, and 90 the pot-mouth adjusted thereto in combination with a wiper to act on the mouth of the pot, a spring-actuated arm to move the wiper in one direction, a stud on the mold-disk to move the wiper in the opposite direction, and means to effect the automatic disengagement 95 of the stud when the wiper reaches its proper limit of movement.

8. In a linotype-machine, a melting-pot and 100 a coöperating mold arranged to meet and to separate, in combination with a wiper mounted to travel across the front face of the pot-mouth, and mechanism to effect the to-and-fro motion of the wiper while the pot and the mold are separated whereby foreign matters adhering to the pot-mouth are removed that 105 it may close tightly against the mold.

In witness whereof I have hereunto set my hand in the presence of two witnesses.

PHILIP CHARLES LAWLESS.
